UNITED STATES PATENT OFFICE.

CARL D. BROWN, OF HOPEDALE, MASSACHUSETTS, ASSIGNOR TO DRAPER CORPORATION, OF HOPEDALE, MASSACHUSETTS, A CORPORATION OF MAINE.

CLOTH-ROLL LOCK.

Application filed November 27, 1925. Serial No. 71,845.

This invention relates to looms, and more particularly to means for locking the cloth roll in the cloth roll stands.

It is now the ordinary practice to provide 5 looms with a cloth roll stand at each side thereof at the front of the loom, and mount the cloth roll on a rack bar which is raised by a train of mechanism to move the cloth roll to its cloth winding position, and in 10 order that the cloth roll may be removed from the loom when the desired length of cloth has been wound thereon as it is woven, each of the cloth roll stands is provided with a roll removing opening which 15 communicates with a guideway usually provided in each stand.

When the cloth as it is woven has been wound upon the cloth roll, the journals of the cloth roll are usually in a position adjacent 20 the cloth roll removing openings in the stands, and at this time there is usually nothing to prevent the cloth roll from jumping out of the loom, owing to loom vibration or from other cause, and accidents are liable 25 to occur to the loom attendant, the loom parts and the cloth.

One of the objects of the present invention, therefore, is to provide a cloth roll lock so constructed and arranged that when 30 the cloth has been wound upon the cloth roll and the journals of the latter are adjacent the cloth roll removing openings in the stands, the lock will prevent accidental removal of the cloth roll and its load, until 35 the loom attendant or other operative intentionally desires to remove the cloth roll and its load from the loom.

More specifically stated, the invention 40 comprises a lock located in the cloth roll removing openings in the cloth roll stands and movable at will to an inoperative position to permit the removal of the full cloth roll and the substitution of an empty one, the construction being such that as the empty 45 cloth roll is moved to its cloth winding position, usually against the sand roll, it will trip the lock for movement again to its locking position.

The invention, the new combination of 50 parts, and the novel features thereof, will best be made clear from the following description and the accompanying drawings of one good form thereof.

In the drawings:

Fig. 1 is a perspective view at the front

of the loom, showing the present invention associated therewith;

Fig. 2 is an enlarged detached detail showing more particularly the lock and its relation to the cloth roll removing opening; and 60

Fig. 3 is an enlarged front view of the parts indicated in Fig. 2 and more particularly showing the lock in the cloth roll removing opening.

The loom frame and loom operating parts 65 for weaving cloth may be of usual character, and in the present instance the side members of the loom frame at the front thereof are connected by a girth or cross-bar 1 which may also be of usual construction, and at 70 the top the sides of the loom frame are connected by a breast beam 2. The girth or cross-member 1 at the lower part of the loom frame has mounted thereon the cloth roll stands, one at each side of the loom. 75 As shown, these stands comprise arms or members 3 of similar construction which are secured at their lower ends to the cross-girth 1 by bolts 4 or similar securing means, and at the top the cloth roll stands are secured to the loom frame, and, as shown, preferably to the breast beam 2, as at 5. There is nothing new in this arrangement of the cloth roll stands, and such stands may be secured 80 in position in any appropriate manner. 85

The breast beam 2, as shown herein, is preferably formed of metal and is of general angular shape in cross-section. Below the upper member 6 of the breast beam, the loom, in the present instance, has a sand 90 roll 7, over which the cloth *a* is drawn towards the cloth roll during the weaving operation. The sand roll 7 is driven, as usual, from a train of mechanism, but as the details of such train of mechanism and the 95 particular means of rotating the sand roll form no essential parts of the present invention, they are not hereafter illustrated and described.

It is usual in some types of cloth take-up mechanism to employ a cloth roll which may be driven by direct surface contact with the sand roll or some intermediate driving roll connected to the take-up mechanism, and so it is usual in take-up mechanisms to provide 100 the cloth roll stands with guideways to embrace and direct the movement of the journals of the cloth roll towards and from the sand roll. To effect movement of the cloth roll to winding position against the sand 105 roll 7, the cloth roll stands are provided with 110

roll a train of mechanism including a yielding member is employed, so that as the cloth roll increases in size and finally has wound thereon the desired length of cloth, 5 the journals of the roll are located adjacent the cloth roll removing openings in the cloth roll stands. In such mechanisms the cloth roll is usually moved to its winding position against the sand roll by a rack bar, 10 and such form of mechanism is herein shown. The cloth roll stands each have a guideway 8 to receive the journals of the cloth roll 9 on which the cloth is to be wound. The guideways 8 may be variously contrived, either as channelways or slots in the cloth roll stands, the essentials being that the journals of the cloth roll will be prevented from jumping out of the guideways.

20 Mounted in the guideways in the cloth roll stands, or otherwise supported, are the rack bars 10 having seats 11 at their upper ends on which the journals of the cloth roll rest. These rack bars extend downwardly and are engaged with the teeth of a gear 12 mounted on a support 13 and having connected therewith a sprocket wheel 14 over which passes the sprocket chain 15. The sprocket chain 15 also passes over the sprocket wheel 16 loosely mounted on the 25 shaft 17 which extends transversely of the loom and is supported in suitable bearings for turning movement. The loose sprocket 16 is connected to the shaft 17 by a spiral spring 18, that is, one end of the spring 18 is connected at 19 to the sprocket 16 and at 30 to a collar 21 fixed on the shaft 17. In the present instance, the spring connection of the sprocket 16 to the shaft 17 is duplicated at each end of the shaft, and between the side frames the shaft 17 is provided with a worm wheel 22 which is engaged with a worm 23 mounted in bearings 24 on the girth 1, and having an opening 25 or similar means for receiving a hand implement or 35 crank handle, the construction being such that when it is desired to move an empty cloth roll upwardly into driving relation with the sand roll, the loom attendant turns the worm 23 and through the described connection with the rack bars 10, the cloth roll is moved upwardly but is, nevertheless, capable of downward movement through the yielding connection between the sprockets 16 and the shaft 17, so that as the cloth is 40 wound upon the cloth roll 9, the cloth roll 9 and its journals will push down the rack bars until finally the journals of the cloth roll will be opposite the cloth roll removing 45 openings in the cloth roll stands. At this time the cloth roll is liable to be thrown from the loom, with possible injury to the loom attendant and loom parts, if means were not provided to overcome this condition.

50 Each of the cloth roll stands has the cloth roll opening 26, which is herein shown

as a part of the stand bent laterally outward in order to permit the journals of the cloth roll to pass freely to and from the guideways in the cloth roll stand. The enlarged openings 26 may be variously contrived, but 55 in the present instance they are formed by bending the cloth roll stands.

60 Mounted in each of the cloth roll removing openings 26 is a lock which, during the weaving operation, is normally in locking position, but which may be removed from locking position at will by the machine attendant, to permit the removal of a full cloth beam and the insertion of an empty one. The locking device is so contrived that 65 when moved manually into its unlocked position, it will retain that position until, as the empty cloth roll is moved upwardly into cloth winding position, it will be automatically tripped for movement to its locking 70 position.

75 In the present instance, the lock comprises a plate or casting 27 having an elongated opening 28 through which passes a pin 29, so that the lock has both a pivotal and bodily movement on the supporting pin 29.

80 At its lower end the lock is provided with a locking toe 30 which is adapted to engage, when in locking position, with a locking shoulder 31 formed in the lower wall of the 85 opening 26.

85 Thus, when the parts are in position as indicated by full lines in Fig. 2, and the cloth roll journals have finally reached the roll removing openings 26, the cloth roll is 90 locked or prevented from jumping out of the roll removing openings. When, however, the loom has been stopped and the loom attendant wishes to remove the cloth roll and its load, the lock is manually moved to an 95 unlocking position, and to this end the lock is provided with a finger lift 32 whereby the lock as a whole may be bodily raised on the pivotal support 29, and then turned into dotted line position, Fig. 2, where it is held 100 by the edge portion 33 of the lock bearing 105 against the surface 34 of the upper wall of the roll removing opening.

110 With the parts in the position as last described, that is, with the lock in its unlocked or inoperative position, as indicated by the dotted lines, Fig. 2, the attendant can remove the cloth roll and its load and insert an empty roll. When the empty roll has 115 been inserted, the attendant winds up the shaft 17 to move the empty roll into cloth winding position, and during the upward movement of the roll it strikes the tumbler portion 35 of the lock and automatically trips the lock from its inoperative position 120 for movement to its operative position, that is, from the dotted line position, Fig. 2, to the full line position. The inclination of the slot 28 in the lock is such that as the 125 journal of the cloth roll lifts the tumbler 130

portion 35 of the lock, the curved edge 36 will permit the tumbler to rise somewhat as the lock turns upon its pivotal support 29 and under the action of gravity, in the present instance, the lock will automatically resume its locking position, as indicated by full lines in Fig. 2.

The construction and details of the locking mechanism, as hereinbefore described, 10 constitute a good practical form of the present invention, but it is to be understood that the details may be varied within the true scope of the invention, which affords a lock, automatically moved to locking position by movement of the cloth roll to its winding position, to thereafter prevent the removal of the cloth roll from the cloth roll stands until the loom attendant intentionally moves the lock to its inoperative or un- 20 locked position.

What is claimed is:

1. In a loom, the combination of a cloth roll stand having a guideway which receives the journal of a cloth roll and a roll removing 25 opening leading into the guideway between the upper and lower ends thereof, a lock for closing the opening and manually movable to its unlocking position to permit the removal of one cloth roll and the insertion of another, and a tumbler connected to the lock for automatically tripping the lock by engagement with the cloth roll as the cloth roll is removed to cloth winding position.

35 2. In a loom, the combination of a cloth roll stand having a guideway for embracing the journal of a cloth roll and a roll removing and inserting opening leading to the guideway, a lock for closing said opening and movable to unlocking position, means for retaining the lock in unlocking position to permit the removal of a full cloth roll and the substitution of an empty cloth roll, and means connected to the lock for tripping the lock that it may move to locking position as the empty cloth roll is moved to cloth winding position.

3. In a loom, the combination of a cloth roll stand at each side of the loom provided 50 with a guideway for embracing the journals of a cloth roll and having a roll removing and inserting opening communicating with the guideway for the removal and insertion of cloth rolls, a lock for closing said opening and manually movable to an inoperative position for the removal and insertion of a cloth roll, means for holding the lock in such inoperative position, and means engaged by the cloth roll as it is moved to winding position to automatically trip the lock that it may move to its closing position.

4. In a loom, the combination of a cloth roll stand at each side of the loom provided 55 with a guideway for the journals of a cloth roll and a roll removing and inserting opening communicating with the guideway, a lock for closing said opening and manually movable to an inoperative position for the removal and insertion of a cloth roll, means for holding the lock in such inoperative position, and means engaged by the cloth roll as it is moved to winding position to automatically trip the lock that it may move to its closing position.

5. In a loom, the combination of a cloth roll stand at each side of the loom provided 60 with a guideway for the journals of the cloth roll and a roll removing and inserting

opening leading to the guideway, a rack bar for yieldingly supporting the cloth roll in the guideway, a lock mounted in the said opening to prevent outward movement of the cloth roll when opposite said opening 70 and movable to an inoperative position at will to permit removal of the cloth roll, and a projection connected to the lock for tripping it for movement to operative locking position by engagement with the cloth roll 75 as the latter is moved upward in the guideway to cloth winding position.

6. In a loom, the combination of a cloth roll stand at each side of the loom provided 80 with a guideway for embracing the journals of a cloth roll and having a roll removing and inserting opening communicating with the guideway for the removal and insertion of cloth rolls, a gravity lock for closing said opening and manually movable to an inoperative position for the removal and insertion of a cloth roll, means for holding the lock in such inoperative position, and means engaged by the cloth roll as it is moved to winding position to automatically trip the 90 lock that it may move to its closing position.

7. In a loom, the combination of a stand having an upwardly extending guideway in which the end of a roll may move bodily and provided with a roll removing and inserting 95 opening communicating with the upwardly extending guideway, a lock for closing the opening to prevent the roll from moving from the guideway through said opening as the roll is bodily moved in the guideway to a position opposite the opening and movable at will from locking position to permit the removal of the roll, and means actuated by the cloth roll as it is moved in the guideway towards cloth winding position to effect automatic movement of the lock back to locking position.

8. In a loom, the combination of a cloth roll stand having a guideway for the journals of a cloth roll and a roll removing and inserting opening communicating with the guideway, a lock for closing said opening to prevent a roll from moving through said opening when the roll is moved in the guideway to a position opposite said opening, and movable at will to unlocking position, and means for effecting movement of the lock to locking position when a cloth roll is moved in the guideway towards cloth winding position.

9. In a loom, the combination of a cloth roll stand having a cloth roll removing and inserting opening, a latch mounted for bodily and pivotal movement in said opening, a locking shoulder engaged by the latch when in locked position and from which it may be disengaged by bodily movement of the latch that the latch may be placed in inoperative position for the removal of a cloth roll, and a part on the latch for en- 130

gagement by a cloth roll to automatically trip the latch for movement back to locking engagement with the shoulder as the cloth roll is moved to cloth winding position.

5. 9. In a loom, the combination of a cloth roll stand having a guideway for the journals of a cloth roll and a roll removing and inserting opening communicating with the guideway, a lock for closing said opening

and movable at will from locking position 10 to permit the removal of a full cloth roll and automatically tripped for movement back to locking position by movement of an empty cloth roll to cloth winding position.

In testimony whereof, I have signed my 15 name to this specification.

CARL D. BROWN.
